UNITED STATES PATENT OFFICE

BARTON R. SHEETS AND CHARLES M. STEWART, OF DENVER, COLORADO, ASSIGNEES TO GARDNER-DENVER COMPANY, OF DENVER, COLORADO, A CORPORATION OF DELAWARE

FLUID OPERATED TOOL

Application filed December 22, 1927. Serial No. 241,853.

The present invention relates to valve mechanism for distributing motive fluid to the piston of a fluid operated tool, and one of the objects is to provide a novel distributing valve, which it has been found materially reduces the vibration that is ordinarily present during the operation of a tool of this character.

Another object is to provide means for controlling the operation of the valve, thereby to stop the piston, and preferably to so stop it that a supply of air or other motive fluid at substantially line pressure will be delivered to the bore of the drill steel or other tool.

15 In the accompanying drawings:

Figure 1 is a longitudinal sectional view of the preferred embodiment of the invention with the piston at the front end of its stroke, and the automatic distributing valve held 20 against movement, also at the front end of its stroke.

Figure 2 is a longitudinal sectional view with the piston approaching its rearmost position and the valve in its rearmost position.

25 Figure 3 is a detail longitudinal sectional view on an enlarged scale showing the piston approaching its foremost position and the valve in its foremost position.

Figure 3a is a detail view of the front end 30 of the tool, and constituting in effect a continuation of Figure 3.

Figure 4 is a cross sectional view on the line 4—4 of Figure 1.

Figure 5 is a cross sectional view on the 35 line 5—5 of Figure 2.

Figure 6 is a cross sectional view on the line 6—6 of Figure 3.

Figure 7 is a detail sectional view substantially on the line 7—7 of Figure 1.

40 In the embodiment disclosed, a cylinder member is employed, including a barrel 8, having an internal longitudinally disposed combined piston and valve chamber 9. A front head 10 is located at the front end of the barrel 8 and a rear head 11 is located at the rear end of the barrel 8. A bushing 12, fitted into the head 10, is provided with an outstanding flange 13, and mounted on the front end of the said bushing in advance 45 of the flange, is a chuck housing 14, in which

is located a rotatable tool holder or chuck 15. This chuck is adapted to receive a drill steel or other tool 16 provided with a central longitudinal bore 17. Between the rear end of the barrel 8 and the rear head 11 is fitted a bushing 18 formed with an internal fluid supply groove 19. In advance of the groove 19 is a distributing groove 20, and in advance of said distributing groove is an exhaust groove 21 that is in communication with an exhaust port 22 formed in the barrel. The bushing 18 is fitted into an enlarged bore of the barrel, and terminates short of the front wall of said bore, forming an annular flange-receiving groove 23. In 55 advance of said groove 23 the barrel is provided with an internal annular exhaust groove 24, from which leads to atmosphere, an exhaust passageway 25. The front end of the barrel is provided with an internal 60 annular distributing groove 26 that is in communication with the groove 20 through the medium of passageways 27.

65 In the chamber 9 is located a tubular reciprocating automatic distributing valve 28, having an external annular flange 29 operating in the flange-receiving groove 23. It is also provided at its rear end with an annular groove 30 that alternately affords communication between the grooves 19 and 20 so when the valve is in its rear position, as shown in Figure 2, and between the grooves 20 and 21 when the valve is in its foremost position, as shown in Figures 1 and 3. Said valve also has in its front end a plurality 70 of ports 31 that are in constant communication with the annular groove 26 in the barrel. The front end of the valve operates freely in a pocket, from which extend to atmosphere relief ports 32. The front end of the said valve 28 is reduced in its external diameter, providing a forwardly faced annular shoulder 33. Said valve is provided in advance of the flange 29 with exhaust ports 34 that are in constant communication with the exhaust groove 24, and thus with the exhaust passageway 25. There are also provided in said valve, trip ports 35 opening from its interior to the ex- 75 80 85 90 95 100 105 110 115 120 125 130 135 140 145 150 155 160 165 170 175 180 185 190 195 200 205 210 215 terior into the flange-receiving groove 23 and in advance of the flange 29.

Motive fluid is supplied to the tool through a nipple 36 (see Figure 7), to which 5 may be coupled a supply hose, and this nipple is at the end of a tapered valve chamber 37, in which is a rotary tapered throttle valve 38, having an axial passageway 39 in communication with the interior of the nipple 36, and provided with transverse outlet ports 40. One of these ports, when the valve is in open position, as shown in Figures 1, 10 2 and 3, is in communication with a passageway 41 that leads to the main supply groove 19, and from said supply groove there is a 15 passageway 42 that will direct a portion of the fluid to the front faced shoulder 33 of the automatic valve, and which will thus constantly urge the valve rearwardly.

20 A reciprocating piston 43 is mounted in the chamber 9 within the automatic distributing valve 28. It is provided with a reduced hammer extension 44 that operates through the bushing 12 and chuck 15 to hammer upon 25 the rear end of the steel 16. This piston preferably has a sliding interlocking engagement 45 with the chuck, so that the latter will be rotated by the former, and said piston is in turn rotated by means of a rifle bar 46, 30 having the usual ratchet mechanism 47 located in the rear head 11. The piston 43 and its extension 44 are provided with a longitudinal passageway 48 opening into the piston chamber behind the piston and in communication 35 with the bore 17 of the steel 16. Preferably there is also provided a water tube 49 mounted at its rear end, as shown at 50 in the rear head 11, and extending longitudinally within the passageway 48. The piston head 43 operates between a point just in rear of 40 the ports 31 of the automatic valve and the rear end of said valve, as will be evident by comparing Figures 1 and 2. In its movement it therefore covers and uncovers the 45 exhaust ports 34 and trip ports 35 of said valve 28.

There is also provided means for closing the exhaust passageway 25 and supplying motive fluid against the rear face of the valve 50 flange 29. To this end the barrel 8 is provided with an enlargement in which is formed a piston chamber 51, and in said chamber is located a piston 52 having a plunger valve extension 53 that is movable 55 to and from a position across the passageway 25 for the purpose of closing said passageway. The piston and valve are urged to their rear positions by means of a coiled spring 54 surrounding the valve and operating against the 60 front face of the piston. A passageway 55 for live motive fluid leads from the passageway 41 in front of the throttle valve 38 to the rear end of the piston chamber 51, and this passageway 55 is controlled by a rotary valve 65 56 having an exposed finger piece 57 arranged

adjacent to the handle of the throttle valve 38. Preferably the piston chamber 51 is provided with relief ports 58 on opposite sides of the piston 52, these ports being of much less area than the supply passageway 55. There is also a passageway 59 leading from the rear portion of the chamber 51 to the valve flange-receiving groove 23 and in rear of the flange 29 when it is in the foremost position in the groove. The passageway 59, it will be noted, is cut off from the passageway 55 when the piston 52 is in its rearmost position, as shown in Figures 2 and 3.

The operation of the mechanism is as follows. Considering Figures 2 and 3, with the 80 controlling valve 56 closed and the throttle valve 38 open, when the piston approaches the rear end of its stroke, with the valve in its rearmost position, as shown in Figure 2, pressure will be built up behind the piston which will operate against the rear end of the valve and shift it forwardly against the pressure of the fluid operating against the shoulder 33 and resisting such movement. When said valve is shifted forwardly, motive fluid from 85 the main supply groove 19 can flow inwardly around the rear end of the valve 28, and operating therein against the rear end of the piston, drive it forwardly. During this forward movement the fluid in advance of the piston head 43 will exhaust through the ports 31, groove 26, passageway 27, groove 20, valve groove 30, exhaust groove 21 and exhaust port 22 to atmosphere. As soon as the piston 90 during this forward movement uncovers the trip ports 35, obviously motive fluid will pass through said ports 35, and operating against the front face of the valve flange 29 will provide sufficient force in addition to that operating against the shoulder 33 of the valve to 95 shift said valve rearwardly. When this occurs, as illustrated in Figure 2, the motive fluid is cut off from entering the rear end of the valve, and at the same time fluid under pressure will now find its way from the main 100 supply groove 19 by way of the valve groove 30, distributing groove 20, passageways 27, groove 26 and ports 31, to act against the front face of the piston head, thereby driving the piston rearwardly. The exhaust now 105 takes place in rear of the piston through the ports 31, groove 24, and exhaust passageway 25. The piston is thus repeatedly reciprocated and delivers hammer blows against the 110 drill steel 16, and at each forward operation a part of the actuating fluid behind the piston will flow through the passageway 48 in said piston, to the bore 17 of the drill steel for ejecting the cuttings from the hole being 115 drilled.

It sometimes happens, however, that an augmented supply of cleansing fluid is required for cleansing purposes. Whenever this becomes desirable, the operator has only to turn the valve 56 from its closed to its 120

open position, whereupon the ports will assume the relation shown in Figure 1. The piston 52 will be moved forwardly against the action of the spring 54 and close the exhaust passageway 25. At the same time this uncovers the passageway 59 and a part of the live fluid under pressure will enter the rear end of the flange-receiving groove 23, thereby operating against the rear face of the flange 29 and either moving forwardly or holding the valve in its forward position, as shown in said Figure 1. The result is that the valve being held in its forward position, live fluid is permitted to continue to enter the rear end of the valve against the rear end of the piston, holding it firmly against the steel 16, and the normal exhaust 34—24—25 is now cut off. The only method of escape for this fluid under line pressure is therefore through the passageway 48 and bore 17 of the drill steel. As soon as the valve 56 is closed the pressure in the chamber 51 drops because of the escape to atmosphere through the ports 58, and the spring 54 can now react to open the valve 53, thereby opening the exhaust 34, cutting down the pressure against the rear face of the valve flange 29 and allowing the valve to assume its normal cycle of operations.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What we claim, is:

1. In a tool of the character set forth, the combination with a cylinder member having a piston chamber and a reciprocatory piston therein, of a holder for a tool to be operated on by the piston, means for supplying actuating fluid to the cylinder member, an automatic valve for distributing such actuating fluid to the piston chamber to operate the piston, means for directing actuating fluid from a point in advance of its entry into the piston chamber, against the valve to hold it in a position to maintain the supply of actuating fluid against the rear end of the piston, an exhaust passageway from the rear end of the piston, and a secondary valve operated by the holding fluid, for closing said exhaust passageway.

2. In a tool of the character set forth, the combination with a cylinder member having a piston chamber and a reciprocatory piston therein, of a holder for a tool to be operated on by the piston, means for supplying actuating fluid to the cylinder member, an automatic valve for distributing such actuating fluid to the piston chamber to operate the piston chamber to operate the piston.

ton, means for directing actuating fluid from a point in advance of its entry into the piston chamber, against the valve to hold it in a position to maintain the supply of actuating fluid against the rear end of the piston, an exhaust passageway from the rear end of the piston, a secondary valve operated by the holding fluid for closing said exhaust passageway, and means for directing fluid from the rear end of the piston to the bore of a tool placed in the tool holder.

3. In a tool of the character set forth, the combination with a cylinder member having a piston chamber and a reciprocatory piston therein, of a holder for a tool to be operated on by the piston, means for supplying actuating fluid to the cylinder member, an automatic valve for distributing such actuating fluid to the piston chamber to operate the piston, means for permitting fluid to exhaust from the piston chamber, means for directing fluid against the automatic distributing valve to hold it against movement and thereby stop the piston, and a valve for alternately closing the exhaust permitting means and the means for supplying the holding fluid.

4. In a tool of the character set forth, the combination with a cylinder member having a piston chamber and a reciprocatory piston therein, of a holder for a tool to be operated on by the piston, means for supplying actuating fluid to the cylinder member, an automatic valve for distributing such actuating fluid to the piston chamber to operate the piston, means for permitting fluid to exhaust from the piston chamber, means for directing fluid against the automatic distributing valve, to hold it against movement and thereby stop the piston, a fluid actuated valve for alternately closing the exhaust permitting means and the means for supplying the holding fluid, and valve controlled means for supplying motive fluid to the fluid actuated valve to effect its movement.

5. In a tool of the character set forth, the combination with a cylinder member having a piston chamber and a reciprocatory piston therein, of a holder for a tool to be operated on by the piston, means for supplying actuating fluid to the cylinder member, an automatic valve for distributing such actuating fluid to the piston chamber to operate the piston, means for directing fluid from behind the piston to the bore of a tool in the holder, an exhaust passageway for the fluid behind the piston, a piston valve movable to and from a position across the exhaust passageway, a passageway for directing fluid from the fluid supply to the piston valve to move it, and means for causing such fluid to operate on the automatic distributing valve and hold it to maintain the fluid supply against the rear end of the piston and thereby hold it in its advance position.

6. In a tool of the character set forth, the combination with a cylinder member having a piston chamber and a reciprocatory piston therein, of a holder for a tool to be operated on by the piston, means for supplying actuating fluid to the cylinder member, an automatic valve for distributing such actuating fluid to the piston chamber to operate the piston, means for directing fluid from behind the piston to the bore of a tool in the holder, an exhaust passageway for the fluid behind the piston, a piston valve movable to and from a position across the exhaust passageway, a passageway for directing fluid from the fluid supply to the piston valve to move it, means for causing such fluid to operate on the automatic distributing valve to hold it to maintain the fluid supply against the rear end of the piston and thereby hold it in its advance position, and a valve for controlling the supply of fluid to the piston valve while permitting the supply of actuating fluid to the rear end of the piston past the automatic distributing valve.
7. In a tool of the character set forth, the combination with a cylinder member having a piston chamber, of a tubular automatic distributing valve in the piston chamber having an external forwardly faced pressure shoulder in rear of its front end and an external flange, said front end operating in a pocket that is open to atmosphere, means for directing rearwardly acting pressure fluid against the shoulder, said valve having a port therethrough for admitting fluid from its interior against the front face of the flange, a piston operating in the piston chamber and valve and covering and uncovering the port, means for supplying motive fluid against the rear end of the valve and past the same to the interior of the valve to operate the piston, and means with which said valve's rear end cooperates to cut off the supply of motive fluid to the interior of the valve.
8. In a tool of the character set forth, the combination with a cylinder member having a combined piston and valve chamber, of means for supplying motive fluid to the rear end of the chamber, said chamber having an internal rear groove and an internal front groove, a passageway in the cylinder member connecting the grooves, said chamber also having an intermediate internal flange-receiving groove, a tubular reciprocating automatic distributing valve in the chamber having a flange in the intermediate groove, said valve having an external groove that affords communication between the fluid supply and the rear groove and also having a port affording communication between the front chamber groove and the interior of the valve, a reciprocatory piston operating in the valve between said port and the rear end of the valve, said valve having a trip port opening into

the flange receiving groove in advance of the flange and said trip port being covered and uncovered by the piston, said valve also having an external forwardly faced shoulder, means for supplying motive fluid constantly against the shoulder, and means for permitting the exhaust of fluid from the interior of the valve on opposite sides of the piston, including a port opening through the valve and covered and uncovered by the piston.

9. In a tool of the character set forth, the combination with a cylinder member having a combined piston and valve chamber, of means for supplying motive fluid to the rear end of the chamber, said chamber having an internal rear groove and an internal front groove, a passageway in the cylinder member connecting the grooves, said chamber also having an intermediate internal flange receiving groove, a tubular reciprocating automatic distributing valve in the chamber having a flange in the intermediate groove, said valve having an external groove that affords communication between the fluid supply and the rear groove and also having a port affording communication between the front chamber groove and the interior of the valve, a reciprocatory piston operating in the valve between said port and the rear end of the valve, said valve having a trip port opening into the flange receiving groove in advance of the flange and said trip port being covered and uncovered by the piston, said valve also having an external forwardly faced shoulder, means for supplying motive fluid constantly against the shoulder, means for permitting the exhaust of fluid from the interior of the valve on opposite sides of the piston, including a port opening through the valve and covered and uncovered by the piston, and an exhaust passageway with which the port communicates, a fluid operated plunger valve for closing the exhaust passageway, and valve controlled means for directing fluid to operate the plunger valve to close the exhaust passageway and simultaneously directing such fluid against the rear face of the valve flange.

10. In a tool of the character set forth, the combination with a cylinder member having a piston chamber and a reciprocatory piston therein, of a holder for a tool to be operated on by the piston, means for supplying actuating fluid to the cylinder member, means for supplying motive fluid to the piston chamber to operate the piston, means controlled by the piston for permitting the exhaust of the fluid from the piston chamber, an automatic valve for distributing fluid to the piston chamber to actuate the piston, a fluid actuated valve for closing the exhaust means, and means for directing fluid to both valves to hold the distributing valve against movement and to cause the fluid actuated valve to close the exhaust means.

11. In a tool of the character set forth, the combination with a cylinder member having a piston chamber and a reciprocatory piston therein, of a holder for a tool to be operated on by the piston, means for supplying actuating fluid to the cylinder member, means for supplying motive fluid to the piston chamber to operate the piston, said cylinder member having an exhaust port opening from the piston chamber and covered and uncovered by the piston on its movement, an automatic valve for distributing fluid to the piston chamber to actuate the piston, a fluid actuated valve for closing the exhaust means, a passageway leading from the motive fluid supply to both valves to hold the distributing valve against movement and to cause the fluid actuated valve to close the exhaust means and a valve controlling the passageway.

20 In testimony whereof, we affix our signatures.
